FREDERICK MARGGRAFF, ONE-FOURTH TO ARTHUR MARGGRAFF, AND ONE-
FOURTH TO HARVEY MARGGRAFF, ALL OF MILWAUKEE, WISCONSIN.

COMPRESSOR FOR REFRIGERATING APPARATUS.

1,307,061.

Specification of Letters Patent. Patented June 17, 1919.

Application filed December 26, 1917. Serial No. 203,846.

To all whom it may concern:

Be it known that I, EDWIN O. OLSEN, a citizen of the United States, and resident of Milwaukee, in the county of Milwaukee and 5 State of Wisconsin, have invented new and useful Improvements in Compressors for Refrigerating Apparatus, of which the following is a description, reference being had to the accompanying drawings, which are a 10 part of this specification.

The invention relates to compressors for refrigerating apparatus.

The invention is designed to provide a compressor of simple construction and consists in the combination and arrangement of 15 the parts as more fully hereinafter described.

The invention is further designed to provide a compressor in which the inlet valve 20 is formed by the piston which opens and closes the inlet port during its movement.

The invention also has for its object to introduce the refrigerant into the compression cylinder upon the top of the piston 25 and to deliver it through a single valve at the upper end of the cylinder.

The invention is further designed to provide a valve seat for the outlet valve which may be readily removed for the purpose of 30 renewal.

The invention further consists in the several features hereinafter set forth.

In the drawings:

Figure 1 is a vertical sectional view 35 through the device embodying the invention, the section being taken on the line 1—1 of Fig. 2;

Fig. 2 is a section taken on the line 2—2 of Fig. 1;

Fig. 3 is a section taken on the line 3—3 of Fig. 2.

The compressor comprises a crank case 4 having a removable end plate 5 secured thereto by bolts 6, the bottom being sealed 45 by securing the base 7 to a suitable support (not shown), a cylinder 9 integral with said crank case, a piston 10 within the cylinder, a crank shaft 11 journaled in bearings 12 mounted in the crank case, means for oper- 50 atively connecting said piston to the crank shaft, and other parts more particularly hereinafter described.

The means for connecting the piston 10 to the shaft 11 consists of a pitman 13 pivotally

connected at one end to the shaft 11 and at 55 its other end to a pin 14 secured within the piston by set screws 15, the piston having a hollow interior portion 16. The working face or top of the piston has a cylindrical recess 17 therein communicating with an 60 opening 18 leading into its interior 16 said opening having a valve seat 19 upon which rests a ball or check valve 20 which is limited in its upward movement by an annular grid 21 secured within the recess 17. This 65 check valve opens when the piston is moving down so as to prevent the formation of a vacuum in the cylinder above the piston and also to permit the outward passage of refrigerant gas which may work into the closed 70 crank case.

An annular receiver or refrigerant chamber 20' is formed integral with the cylinder and surrounds a portion of the same. It is provided with an inlet 23 and an outlet port 75 24 which is so positioned as to allow the refrigerant in the chamber to enter the cylinder when the piston has moved down to its lower position and which is closed by the piston when it moves upwardly, the piston 80 thus performing the functions of an inlet valve.

The upper part 25 of the cylinder is provided with a water jacket 26, part of which is formed integral with the cylinder and the 85 other part is formed by a head 27 which is removably secured to the main portion of the compressor by bolts 28'. The cooling water passes from a pipe 29 into the jacket and out through a pipe 30. 90

Within the head 27 and formed integral therewith is the cylinder head 31 having an outlet conduit 32 leading therefrom, said head being surrounded by the water jacket 26. 95

The top of the cylinder is provided with a cylindrical recess 27' in which a valve seat 28 is removably secured by clamping it between said cylinder and the head 27. The connection between the head 27 and the cylinder and outer jacket walls 26' is made tight by providing annular recesses 33 and 34 in the cylinder and outer jacket wall, respectively, into which fit packing rings 35 and 36 and annular ribs 37 and 38 on the 105 head 27.

Seated upon the seat 28 is an outlet valve 39, the stem 40 of which is slidably mounted

- in a bore 41 in the cylinder head, the valve being held to its seat by spring 42 interposed between it and the head 31. To prevent the refrigerant working up into the space above 5 the valve stem and increasing the pressure upon the same a by-pass 43 is provided in the stem establishing communication between the cylinder head and the portion of the bore 41 above the valve stem. A purge cock 10 44 is mounted on the head in communication with the bore 41 to which a hose (not shown) may be attached to draw off the refrigerant when desired.
- The compressor may be driven by a suitable source of power connected to the crank shaft 11 and in the present instance I have shown a fly wheel 45 on the shaft carrying a belt 46 which is adapted to be connected up to an electric motor (not shown).
- 15 20 The working parts of the compressor are kept well oiled by introducing oil in the crank case through a suitable inlet and allowing it to partially fill the same, the oil passing out through a suitable outlet in said case in the usual manner.

With this construction the refrigerant gas in the chamber 20' passes and is sucked into the cylinder 9 above the piston 10 through the port 24 when the piston moves downwardly to uncover said port. During its downward travel the ball valve 20 is raised from its seat so as to establish communication between the upper portion of the cylinder and the crank case to prevent the formation of a vacuum in that portion of the cylinder in front of the piston. During the upward stroke of the piston the port 24 and valve 20 are closed by the piston and the refrigerant is then compressed in the cylinder.

der between its head and the piston. When 40 the desired pressure has been reached, that is, when the gas has been liquefied, the resistance of the spring 42 is overcome and the valve 39 opens to permit the passage of the liquid refrigerant into the cylinder head 31 from whence it passes out through the conduit 32.

From the foregoing description it will be observed that the construction is very simple and as I am aware that the details of construction are capable of some modification and change I desire it to be understood that such changes as come within the scope of the appended claim I deem to be within the spirit of my invention.

50 55 What I claim as my invention is:

A compressor of the kind described, comprising a cylinder having a refrigerant chamber provided with an inlet and an outlet communicating with the cylinder, a piston in said cylinder adapted to open and close said outlet, a head-section secured on the cylinder and formed with a cylinder-head provided with an outlet conduit, an outlet valve mounted in the head-section to 60 65 control the flow of the refrigerant from the cylinder to the head outlet, said outlet valve being provided with a stem slidably mounted in a bore formed in the head-section, and said stem being provided with a by-pass to 70 establish communication between the space above the outlet valve and the space above the valve-stem, and a normally closed purge-cock connected to the valve-stem bore to draw off the refrigerant when desired.

75 In testimony whereof, I affix my signature.

EDWIN O. OLSEN.
